(**) Term: **14 Years**

(57) **CLAIM**

The ornamental design for a geared half ball component for a rotational valve, as shown and described.

(21) Appl. No.: **29/425,483**

(22) Filed: **Jun. 22, 2012**

DESCRIPTION

(30) **Foreign Application Priority Data**

Dec. 22, 2011 (AU) 201115921

FIG. 1 is a perspective view of a geared half ball component for a rotational valve according to the present invention;

(51) **LOC (9) Cl.** **23-01**

FIG. 2 is a top view of the geared half ball component for a

(52) **U.S. Cl.**

rotational valve of FIG. 1;

USPC **D23/233**

FIG. 3 is a bottom view of the geared half ball component for a

(58) **Field of Classification Search**

rotational valve of FIG. 1;

USPC D23/233–237, 244–249; 251/360, 363;

137/515.5, 515; 4/249, 250, DIG. 3

See application file for complete search history.

FIG. 4 is a front view of the geared half ball component for a
